SPARK PLUG

Filed Jan. 7, 1928

Inventor:
Emrich Stern

By his Atty. Louis B. Goldfarb.

UNITED STATES PATENT OFFICE

EMERICH STERN, OF TEMISOARA, RUMANIA

SPARK PLUG

Application filed January 7, 1928, Serial No. 245,162, and in Austria April 27, 1927.

This invention relates to improvements in spark plugs which essentially consist in that a clamping device is conductively connected with the screw-threaded end of a 5 spark plug, whereby one or more removable electrodes are inserted in and fixed in position by the said clamping device. In case the spark plug is contaminated with oil or soot, the electrode can be removed in a most 10 simple manner, cleaned and re-inserted into the spark plug or replaced by another electrode.

Further the present invention relates to a 15 tool for inserting the removable electrode into the clamping device of the spark plug.

The present invention is illustrated by way of example on the accompanying sheet of drawings in which:—

Figs. 1 and 2 show a spark plug in part- 20 sectional elevation and in inverted plan view respectively.

Fig. 3 shows a tool for inserting the electrode in the spark plug.

Flexible arms 3 of a conducting material 25 and provided with notches or depressions 2, are secured to the screw-threaded end 1 of the spark plug in any convenient manner. An annular electrode 4, introduced into the notches 2, is clamped in position by the said 30 flexible arms 3, which form a clamping device, and the ignition pin 5 of the spark plug passes through the central hole of the electrode. In case the spark plug is contaminated with oil or soot, the resilient arms 35 3 are forced outward to such an extent, that the annular electrode 4 drops out. Now the latter, as well as the spark plug can be cleaned, and the cleaned electrode or a spare 40 electrode is forced into the resilient clamping device.

A tool illustrated in Fig. 3 facilitates the 45 insertion of the electrode in the clamping device. The former consists of a handle 6, a flange 7 formed upon or secured thereto in- 50 termediately of its ends, and at its other end is fashioned as a pin 8, which is provided with a hole or excavation 9 for the admission of the ignition pin 5 of the spark plug. The annular electrode 4 is placed onto the 55 flange 7 and now the tool together with the

electrode is pushed into the spark plug, whereby the ignition pin 5 enters the hole 9 of the pin 8 and the resilient arms 3 are forced apart by co-operating with rim of the electrode, until the latter snaps into the notches 2 of the arms 3. A concentric introduction of the electrode is rendered possible in a most simple manner by the aid of the tool above mentioned.

I claim:—

1. A spark plug comprising a resiliently expandable clamping device conductively connected with the screw-threaded end of the spark plug, and an electrode removably inserted in and yieldingly held in position by the said clamping device.

2. In a spark plug, a plurality of clamping elements flexibly projecting from its screw-threaded end, and an electrode detachably clamped in position between the said clamping elements.

3. A spark plug comprising flexible conducting arms circumferentially arranged and connected with the screw-threaded end of the spark plug, said arms being fashioned with opposite notches and a removable annular electrode inserted between and secured in position by the said arms.

In testimony whereof I affix my signature.
